ENDSTONE CAP ASSEMBLY

Ernest W. Drescher, Manheim Township, Lancaster County, Pa., assignor to Hamilton Watch Company, Lancaster, Pa.

Application February 23, 1949, Serial No. 77,769

1 Claim. (Cl. 58—140)

1

This invention relates to a balance endstone cap assembly and the method of making the same.

The endstone cap assembly serves as a means for supporting the balance staff and as a center about which the regulator pins are turned. The entire assembly is supported in the balance cock and is disassembled for even the smallest of repair jobs on the watch. To prevent reshaping of the overcoil of the hairspring to conform to the path of the regulator pins, it is necessary that when the endstone cap assembly is replaced in the balance cock that the same concentricity be maintained as was formerly present before the parts were disassembled. With the present day construction, it is impossible to return the parts to the exact same relative position because the tolerance is greater in the setting of the endstone cap assembly than the distance between the regulator pins and the hairspring overcoil. This necessitates reshaping of the overcoil and a possible throwing of the watch out of time necessitating a retiming of the watch, which requires a long period of time.

The object of the present invention is to provide a method of making and assembling an endstone cap assembly with the balance cock so that after the overcoil of the hairspring has once been shaped to conform to the path of the regulator pins and after a subsequent disassembling of the parts, the reassembling operation will return the parts to the same relative positions which they occupied before being taken down. This relieves the necessity of reshaping the overcoil of the hairspring.

A further object of the present invention is to provide an endstone cap assembly in which a relative concentricity of all its parts with the balance cock is maintained through repeated assembling and disassembling operations.

A still further object of the present invention is to provide a cam locking means for holding the parts in tight relationship.

A still further object of the present invention is the method of making the endstone cap so that the tolerance in fitting the endstone cap to the balance cock may be maintained at a minimum.

A further object of the present invention is to provide a circular contact in the balance cock into which the endstone cap assembly is fitted so that the assembling and disassembling of the endstone cap and balance cock will make no change in the concentric relation one with the other.

A still further object of the present invention

2

is to provide three points of contact by means of which the endstone cap may be assembled with the balance cock repeatedly without disturbing the concentric relation of the two.

5 It is a further object of the present invention to provide an endstone cap formed with swedged feet and having an interrupted circumference to serve as a bearing for the regulator.

The invention is shown in the accompanying 10 drawing in which:

Figure 1 is a top plan view of the assembled invention.

Figure 2 is a section on line 2—2 of Figure 1.

15 Figure 3 is a bottom view of the endstone cap, showing the original endstone cap in dotted lines and the finished turn cap in solid lines.

Figure 4 is a bottom view of the endstone cap and balance cock, particularly showing the cam used to wedge the two together.

20 Figure 5 is a cross sectional view of the endstone cap showing the original extent of one of the pins on the dotted lines.

Referring more particularly to the drawing, 25 the balance cock 7 is shown supporting the endstone cap 8 which is fitted with the endstone jewel 9 and carries the regulating arm 10.

This endstone cap 8 serves as a center pin for the regulating arm 10 and as the endstone cap is mounted in the balance cock 7, the closeness of fit between the endstone cap and the balance cock is extremely important as regards the movement of the regulator arm with relation to the balance cock.

30 Mounted in the balance cock 7 is the olived hole jewel 11 which serves as a pivot for the balance staff 12 on which is mounted the collet 13. A hairspring 14 is secured to the collet 13. The outermost coil 15 of the hairspring is overcoiled and formed, for a small section, in a true circular curve which conforms to the path of the regulator pins.

35 When the watch is taken apart for cleaning, the reassembling of the endstone cap and balance cock is extremely important to the timekeeping 45 of the watch as the outermost coil of the hairspring must resume its exact position in order for the regulator pins to function. It is, therefore, necessary that the endstone cap and balance cock be reassembled in exactly the same relationship 50 as they were before.

As is well known, the regulator pins change the effective length of the hairspring by the pivoting of the regulator arm about the endstone cap, moving the pins on that section of the hairspring 55 which conforms to the path of the regulator pins.

It is, therefore, seen how necessary it is that the regulator pins move in a curve which has as its center the endstone cap.

In the formation of an endstone cap which can be effectively removed and replaced on a balance cock and maintained in original position, a blank cap is formed as shown in dotted lines in Figure 3 at 17 and feet 18 are swedged on the cap. A turning operation produces a configuration shown in solid lines in Figure 3 at 19 having three lips 20 of slightly larger diameter than the main body 21 of the cap. In the turning operation the outside edges of the pin 22 are turned to the same diameter as the body of the cap producing in effect a cylinder which is fitted into the holes 23 of the balance cock.

The pins 18 are undercut as at 24 on their inward surfaces and a cam 25 having pin engaging cam surfaces 26 is turned by means of a screw slot 27 into engagement with the undercut portions of the pins to draw the endstone cap downward against the balance cock, the cam bearing against the balance cock at 27 (Figure 2).

What is claimed is:

An endstone cap and balance cock assembly, comprising a balance cock formed with three openings, the centers of which are concentric with

a central opening, said central opening being formed to receive the olived hole balance staff pivot jewel, an endstone cap having downwardly projecting pins integral therewith, the outside diameter of all of said pins being equally distant from a center point, the pins being receivable in the three holes of the balance cock, means engaging the inside of the pins to lock the endstone cap and balance cock together, whereby the endstone cap is held concentric with the olived hole balance staff pivot jewel.
